UNITED STATES PATENT OFFICE.

WILLIAM HUGHES, OF TAUNTON, MASSACHUSETTS, ASSIGNOR TO UNITED SHOE MACHINERY CORPORATION, OF PATERSON, NEW JERSEY, A CORPORATION OF NEW JERSEY.

DESIGN FOR A SHOE.

Application filed June 28, 1927. Serial No. 22,592. Term of patent 14 years.

To all whom it may concern:

Be it known that I, WILLIAM HUGHES, a citizen of the United States, residing at Taunton, in the county of Bristol and Commonwealth of Massachusetts, have invented a new, original, and ornamental Design for Shoes, of which the following is a specification, reference being had to the accompanying drawing, forming a part hereof.

The drawing is a perspective view of a

shoe embodying my new design, the dominant feature of which consists in rows of eyelets having perforations in their flanges whereby ornamental panels of the shoe upper are exposed to view within the perimeters of the flanges.

I claim:

The ornamental design for a shoe, substantially as shown and described.

WILLIAM HUGHES.
